[57] ABSTRACT

The invention is a toy for use in a body of water, e.g., a bathtub, a pool or the like. The toy comprises a body typically in the shape of submarine, fish or aquatic mammal, e.g., a whale. The toy normally has a negative buoyancy in water and is pivotally mounted in water with its pivot point located intermediate its ends. Means are provided for feeding air to the lower side of one end of the body. The body is adapted to trap sufficient air to impart positive buoyancy to that end, whereupon the buoyant end rises in the liquid and causes the toy to pivot. The gas trapped in the buoyant end is released when that end has risen to a predetermined level.

1
AQUATIC TOY

This invention relates to a water toy and more particularly to a device for use in a body of water such as a bathtub, a pool and the like.

The primary object of this invention is to provide a new water toy.

An additional object is to provide a novel water toy that is relatively simple, can be made at modest cost and is safe and durable.

A further object is to provide a novel water toy which may be used as an aeration device in aquariums.

Still another object of the invention is to provide an action toy which requires active participation by the user.

The foregoing and other objects hereinafter described or rendered obvious are achieved by means of a water displacing body, typically in the shape of a submarine, fish or aquatic mammal, which is adapted to be pivotally disposed in a body of water, e.g., a bathtub, swimming pool or the like. The body normally has a negative buoyancy in water and is ballasted or mounted so that one end falls in the water. Means are provided by which air can be injected below the ballasted end, e.g., by the breath of the user, and the body is adapted to trap the air under the ballasted end so as to render that end buoyant, whereby the ballasted end rises in the water and causes the body to pivot. The body is further adapted to release air trapped under the ballasted end as it rises whereby the ballasted end again assumes negative buoyancy and consequently begins to fall. The body pivots cyclically in the water when air is introduced continuously.

Other features and advantages of the invention are described or rendered obvious in the following detailed description which is to be considered together with the accompanying drawings wherein:

FIG. 1 is a plan view, partly in section, of an embodiment of a water toy constructed in accordance with the invention;

FIG. 2 is a side perspective view of the water toy of FIG. 1; and

FIG. 3 is a side view, partly in section, of a modification of the invention.

Referring now to FIGS. 1 and 2, the illustrated water toy is shaped and decorated to resemble a whale. Thus it comprises an elongate hollow cylinder-like body 2, a tail 6, fins 7 and eyes 8. The toy also includes a centrally located baffle plate 10 that is located within and extends transversely of the longitudinal axis of body 2. Preferably the baffle plate 10 extends completely across the interior of the body and divides it into two separate compartments A and B. The body is pivotally mounted to a support structure 14 which in the embodiment shown is in the shape of an "S" hanger comprising end members 16 and 18, top and bottom members 20 and 22, and side member 24. This is accomplished by means of an axle or pivot shaft in the form of a hollow pipe 26 that is affixed to the end member 16 of the S-shaped hanger and extends through aligned holes in opposite sides of the body 2. The axle is located at approximately the middle of body 2, but on one side of the baffle 10, i.e., in compartment A. The body 2 is rotatable on axle 26 and is restrained against sidewise movement by spacers 28 mounted on the axle. One end of axle 26 is closed off by end cap 30; the other end is

2

coupled to a flexible hose 32. That portion of pipe 26 located within the body 2 has a series of spaced holes 34 located in a line.

The body has a relatively small discharge opening 36 5 in its top wall at the front end of compartment A, and a relatively large discharge hole 37 in the bottom wall of that compartment. Another discharge hole 38 is also provided at the rear end of body 2. The bottom of compartment B is open as shown at 39.

10 The body 2 and the support structure 14 have a negative buoyancy in water. By way of example but not limitation, the body 2 and support structure 14 all may be made of metal or a plastic material. Preferred are non-toxic shatter proof plastics. If necessary, as when the body 2 or its supporting structure is made of a light weight plastic, the apparatus may be ballasted as by metal weights (not shown).

It is also desirable for the body 2 to be slightly unbalanced on the pivot shaft so as to assure that compartment A is heavier so that it will commence to oscillate as hereinafter described upon introduction of air. If the body is not lightly unbalanced, ballast, e.g., in the form of lead weight 44, is secured to the body in compartment A.

20 FIG. 3 shows another embodiment of the present invention. The embodiment of FIG. 3 differs from that of FIGS. 1 and 2 in that the support comprises a free standing base 50 to which is affixed upright telescoping members 52a and 52b. Members 52a and 52b are hollow and have a plurality of aligned holes 54 into which a pin 56 is removably inserted. Base 50 may be solid; alternatively, it may be hollow and filled with a suitable ballast, e.g., sand, so that the base together with the 25 pivotable body will have a negative buoyancy in water. The hollow axle 26 is mounted in the upper vertical hollow member 52b and projects laterally from the latter far enough to permit the body 2 to be rotatably mounted thereon in the manner illustrated in FIG. 2. The height of the body 2 above the base may be adjusted by telescoping the members 52a and 52b and locking them together by pin 56.

30 Use of the toy will now be described. The toy is mounted in a pool of water, e.g., in a bathtub, so that the body 2 is at least partly submerged. The hanger 14 may be hung over the edge of a bathtub while the base 50 of FIG. 3 will rest on the bottom of the tub. Compartments A and B fill with water and compartment A 35 will fall due to its greater negative buoyancy as a result of ballast 44. The user then blows air into the free end of hose 32. Since the body is inclined, all the air will first tend to be concentrated in compartment A adjacent baffle plate 10. The air introduced will displace 40 the water in compartment A away from the baffle towards the discharge openings 36 and 37. As the amount of air supplied is increased and displaces more of the water out of compartment A via opening 37, compartment A will begin to assume a positive buoyancy 45 and will begin to rise, i.e., the body will pivot clockwise. The body will continue to pivot in this direction until such time as compartment A has moved up far enough for the air trapped in compartment A to reach hole 36, at which time the air will commence to escape through the hole. Compartment A will then 50 commence to again fill with water and it will begin to drop. As compartment A drops, water and air escape 55

through discharge hole 36. Notwithstanding, continued inflow of air from hose 32 will again commence to be concentrated in compartment A whereupon the incoming air will again cause compartment A to rise and the body to pivot in the manner described above. The body will thus pivot about axle 26 in a cyclic manner with a frequency depending on the number, size and position of holes 36, 37, the volume of the compartment A, and the rate of incoming air.

It is to be noted that hole 36 serves two functions. The first function is to determine the angle to which the body will pivot before the air trapped by compartment A is allowed to escape. The second function is to release the air in small bubbles as compartment A begins to fall so that the toy whale will "blow-off" water. Also, when the toy is used in a water where there is soap on the surface, the toy may blow bubbles. It will be appreciated that the hole 36 can be omitted, in which case the body will tend to pivot to a greater angle in the water until such time as the gas trapped in compartment A can escape from hole 37.

It is further to be noted that holes 38 and 39 serve to allow water to pass freely through compartment B as the body pivots. It will be appreciated that holes 38 and 39 can be omitted and compartment B sealed and balanced to equal the density of water. While the toy will thus pivot in a cyclic manner without holes 38 and 39, it is not as desirable since such arrangement may be more expensive to manufacture, and may have more drag in the water.

While the pivot axis has been shown as parallel to the baffle, it will be appreciated that the two do not need to be so aligned. However, the baffle should be adapted to direct air to compartment A of the body as herein described. It also is obvious that the pivot axis need not be at the midpoint of the pivotally mounted body.

In the above description it is contemplated that the pivotal body be positioned slightly below the water level in the tub so that its ends alternatively rise out of the water as it oscillates on its pivot axle. It should be understood however, that the toy will function while completely submerged since air trapped in the chamber A will escape from the vent hole 36 or via the hole 37 when the head end of the body rises to a suitable level.

Of course, it is not necessary that the pivoting body be shaped as a whale as shown. Thus, for example, the

body may be shaped in the form of other sea creatures such as porpoise, sailfish and the like, or the body can be in the shape of a submarine. It will be seen from the foregoing that in addition to being a source of amusement the device of the present invention can be used as a decorative aerating device for aquariums and the like. In such embodiment a continuous air feed such as air pump may be attached to the free end of hose 36. Still other advantages are believed to be obvious to persons skilled in the art.

What is claimed is:

1. A water toy comprising a body in the shape of a fish or aquatic mammal that normally has a negative buoyancy in water; support means pivotally supporting said body with its pivot located intermediate its ends so that said body can undergo a seesaw motion whereby one of said ends is alternatively higher and lower than the other of said ends; said body being unbalanced so that one end normally falls; said body also being adapted to trap at said one end a quantity of air sufficient to exert a positive buoyancy force to said end and having means for releasing the air trapped at said one end when said end is higher than the other end thereof so as to eliminate the positive buoyancy force exerted by said trapped air, and means for directing air to said one end.
2. A toy according to claim 1 wherein said means for releasing air comprises one or more holes at said one end.
3. A toy according to claim 2 wherein said body also has holes at said other end so that water can flow through said other end.
4. A toy according to claim 1 wherein the pivot axis of said body is located to one side of its center of gravity.
5. A toy according to claim 1 wherein said support means comprises a tubular axle on which said body is relatively mounted, said tubular axle having at least one hole through which air can be injected into said body.
6. A toy according to claim 5 wherein said body includes a baffle for directing air injected via said tubular axle into said one end thereof.
